ARTHUR D. PORTER, OF SOMERVILLE, NEW JERSEY, ASSIGNEE TO WALTER MORSE
DE WITT, OF SOMERVILLE, NEW JERSEY.

SPARK-PLUG.

1,276,566.

Specification of Letters Patent. Patented Aug. 20, 1918.

Application filed March 22, 1917. Serial No. 158,362.

To all whom it may concern:

Be it known that I, ARTHUR D. PORTER, a citizen of the United States, residing at Somerville, in the county of Somerset and State of New Jersey, have invented certain new and useful Improvements in Spark-Plugs, of which the following is a specification.

This invention relates to an improved spark plug and has as its primary object to provide a device of this character having two distinct spark gaps so that two distinct sparks will be formed each time current is passed through the plug.

15 The invention has as a further object to provide a spark plug having a main electrode, a ground electrode, and a neutral electrode interposed between the said first mentioned electrodes so that current flowing through the main electrode will first be caused to jump from the main electrode to the neutral electrode to form one spark and will then be caused to jump from the neutral electrode to the ground electrode to form 25 another spark.

And the invention has as a still further object to provide a spark plug which will be of simple construction and which may be employed in connection with substantially 30 any conventional type of internal combustion engine.

Other and incidental objects will appear as the description proceeds and in the drawings wherein I have illustrated the preferred 35 embodiment of the invention and wherein similar reference characters designate corresponding parts throughout the several views:

Figure 1 is a side elevation of my improved spark plug,

Fig. 2 is a sectional view more particularly showing the construction of the plug and the mounting of the electrodes thereon, and

Fig. 3 is a bottom plan view particularly showing the disposition of the electrodes at the spark gaps therebetween.

In carrying out the invention, my improved spark plug is formed with a metallic shell 10, the lower extremity of which is screw threaded so that the plug may be connected in the usual manner with an engine cylinder. Removably fitted through the shell is a porcelain 11. The term porcelain, as here used, is meant to include any

approved character of insulating material formed into a body similar to the porcelain 11. The porcelain 11 is formed intermediate its ends with an annular shoulder 12 confronting a similar shoulder 13 within the shell and interposed between the said shoulders is a spring packing washer 14. Screw threaded into the upper extremity of the shell to surround the porcelain 11 is a nut 15 connecting the porcelain with the shell 16 and interposed between the said nut and the shoulder 12 of the porcelain, is a spring packing washer 16 similar to the washer 14.

Fitted through the porcelain 11 is a main or energized electrode 17, the upper extremity of which extends axially of the porcelain and is enlarged and screw threaded to receive a binding nut 18. Fitted over the upper end of the porcelain is a metallic cap 19 with which the nut 18 is arranged to cooperate for connecting a circuit wire, as conventionally illustrated in the drawings, with the spark plug. Of course, an ordinary nut may be substituted for the cap if desired. At the inner extremity of the threaded portion of the electrode, the porcelain 11 is provided with a recess 11' and the electrode at the said recess is reduced as shown at 17'. The recess is filled with a suitable cement engaging in the reduced portion 17' of the electrode for connecting the electrode with the porcelain. The lower extremity of the electrode 17 is bent longitudinally from the reduced portion 17' to project eccentrically through the porcelain and, at its outer end, 90 extends below the lower end of the porcelain adjacent one side thereof.

Connected to the shell 10 below the lower end of the porcelain 11 is a ground electrode 20 which projects tangentially into the shell from the wall thereof and embedded in the lower extremity of the porcelain or otherwise connected thereto, is a neutral electrode 21, the lower extremity of which is provided with a laterally directed arm or terminal 22 arranged as particularly shown in Fig. 3, between the electrodes 17 and 20 in spaced relation thereto. As illustrated in Fig. 2, the lower extremity of the electrode 17 as well as the outer extremities of the electrodes 20 and 21 is housed within the lower end of the shell 10.

As will now be observed upon reference to Fig. 3, one spark gap is provided between the main electrodes 17 and the neutral electrode 21.

21 while a second spark gap is provided between the said neutral electrode and the ground electrode 20. Accordingly, when current is passed through the main electrode, the current will first jump from the main electrode to the neutral electrode 21 to form one spark and will then jump from the neutral electrode to the ground electrode 20 to form a second spark. Two distinct 10 sparks will thus be formed each time the main electrode is energized. I accordingly provide an arrangement tending to materially enhance the dependability of the plug for giving a positive ignition. Furthermore, the plug is of such construction that it may be used in connection with substantially any conventional type of combustion engine.

Having thus described the invention, what 20 is claimed as new is:

1. A spark plug including a shell, a porcelain fitted therethrough and provided internally with a recess, a main electrode fitted through the porcelain and formed with a 25 circumscribing reduced portion providing at opposite extremities thereof shoulders upon the said electrode, the said reduced portion being disposed within the said recess, a filler within the recess of the porcelain and mold-

ed into the reduced portion of the said electrode to engage said shoulders for connecting the electrode with the porcelain, and a ground electrode carried by the shell to co-operate with the main electrode.

2. A spark plug including a shell, a porcelain fitted therethrough and provided with an internal recess, a main electrode fitted through the porcelain and formed with a circumscribing reduced portion providing at opposite extremities thereof shoulders 40 upon the electrode and weakening the electrode at the said reduced portion to be bent longitudinally and project beyond the inner end of the porcelain adjacent one side thereof, the reduced portion of the electrode being disposed within said recess, a filler arranged within the recess to mold into the reduced portion of the electrode and engage said shoulders for connecting the electrode with the porcelain, a ground electrode projecting into the shell from the lower extremity thereof, and a neutral electrode mounted upon the lower extremity of the porcelain and projecting between the main and ground electrodes to co-operate there- 45 with.

In testimony whereof I affix my signature.
ARTHUR D. PORTER. [L. s.]
